TRAFFIC SIGNAL

John P. Meehan, Los Angeles, Calif.

Application June 8, 1931, Serial No. 542,733

1 Claim. (Cl. 177—329)

This invention relates to traffic signals and, particularly, to intermittently electrically illuminated signals.

An object of the invention is to provide a portable electrically illuminated traffic signal.

Another object is to provide a traffic signal of simple and cheap construction.

Still another object is to provide a traffic signal comprising a head and supporting column, in which electrical connection between the head and column are automatically made when the head is mounted on the column.

Briefly, the invention contemplates a light weight traffic signal comprising an indicating head supported by a relatively small tubular column, with a source of electric energy for illuminating the head, concealed in the tubular column. The source of energy is secured to an inner frame that can readily be inserted in or re-

20 moved from the tubular column.

The construction and operation of my traffic signal is explained in detail in the following specifications taken in connection with the drawing in which

25 Figure 1 is an elevational view of the complete signal with the column broken to contract the drawing;

Figure 2 is a detail, elevational view of the signal head and the upper portion of the column, 30 partly in section;

Figure 3 is a vertical section through the head and upper part of the column in a plane at right angles to the plane of Fig. 2;

Figure 4 is a horizontal section of the upper 35 part of the column in the plane IV—IV, shown in Fig. 3;

Figure 5 is a vertical section through the column showing the batteries used as the source of electric energy;

40 Figure 6 is a horizontal section in the plane VI—VI in Fig. 5.

Referring to Fig. 1 of the drawing, my traffic signal comprises as its main elements a head comprising a display plate 1 attached to a base 45 plate 2 by a vertical tubular column 3. Plate 1 has openings stenciled therethrough outlining any suitable word or design. In the illustration, the word "Stop" is shown, since these traffic signals are most commonly used to halt traffic 50 at intersections. The word displayed is made readily visible at all times and particularly at night by mounting a lamp back of the plate 1.

In the particular embodiment of the invention illustrated, this lamp consists of a neon tube 4 55 formed in a loop, as shown, and having terminal

members 5 and 6. The lamp is enclosed by a sheet metal shield 7 secured to the plate 1 by rivets, as shown in Figs. 1, 2 and 3. The neon tube is supported in proper position by means of screws 9 passing through a recessed lower 60 portion 10 of the shield, into flanges 11 on the terminals 5 and 6 of the tube. The recess portion 10 of the shield 7 may be formed integrally with the shield or, as shown in Fig. 3, it may be formed from a separate piece of metal and welded 65 or riveted to the base of an opening in shield 7.

Terminal tubes 5 and 6 on the neon tube are of porcelain or other insulating material through which are extended metal conductors from the tube 4 to terminal plates 12 and 13. Plates 12 70 and 13 are securely fastened to tubes 5 and 6 by bolts 14 passing through the terminal tubes.

The plate 1 and shield 7 are secured to the upper part of column 3 by a collar 15, the upper end of which is shaped to fit about the shield 75 7, and is riveted thereto, one of the rivets being shown at 16 in Fig. 3. The lower part of collar 15 is shaped to form a tubular opening slightly larger in diameter than column 3. A shoulder 32 rests on the top of column 3 in as- 80 sembed position.

The signal shown in Fig. 2 is adapted to be operated from an ordinary commercial light socket and comprises, in addition to the head and lamp already described, a flashing switch 85 17 and transformer 18 for intermittently supplying current of suitable potential to the terminals 12 and 13 of the lamp. The flashing switch 17 and transformer 18 are attached to an inner tubular member 19 adapted to slip with- 90 in the tubular column 3 and hang from the top edge thereof. This result is obtained by securing the tubular case 19 to another tubular member 20 having a flange 21 adapted to rest on the top edge of column 3, (referring to Fig. 3), the 95 outer edge of flange 21 being flush with the outer circumference of tube 3 to permit the socket member 15 to slip freely over the top of column 3. Tubular members 19 and 20 have inwardly projecting flanges formed on their upper 100 and lower edges, respectively, as shown, and these flanges are secured together by bolts 22.

An insulating disc 24 of "Bakelite", hard rubber or similar material, having a diameter slightly smaller than the inside diameter of tube 3, 105 is positioned between the flanges on tubular members 19 and 20 and clamped therebetween by the bolts 22. A metal disc 25, somewhat smaller in diameter than the inner diameter of the flange 26 on the member 20, is secured to the 110

center of the insulating plate 24 by a bolt 27. Disc 25 serves as one terminal for the secondary winding of transformer 18, and the case comprising tubular members 19 and 20 serves as the other terminal, the connecting leads from the transformer winding being secured under nuts on bolts 27 and 22, respectively.

Connections between the neon lamp terminal 12 and plate 25, and neon lamp terminal 13 and flange 26, are completed by spring brushes 29 and 30, respectively, which are soldered or otherwise firmly attached to terminal plates 12 and 13, respectively, and bear on plate 25 and flange 26, respectively.

15 The embodiment of the invention illustrated in Fig. 2 will ordinarily only be used in a permanent installation, in which case connection from the flasher switch 17 will usually be made through a conductor cord 31 extending down through column 3 to an underground power supply circuit. In assembling this device the tube 3 is permanently fixed in position, connections made between the cord 31 and the switch 17 and then the inner assembly 20, comprising members 19 and 20, inserted through the top of the tube until flange 21 on tubular member 20 rests on the top edge of tube 3. The head, comprising plate 21, shield 7 and socket member 15, is then dropped over the tube 3 until flange 32, projecting from the inner circumference of socket member 15, rests on the top of flange 21.

In this position, referring to Figs. 3 and 4, spring 29 attached to plate 12 rests on and makes contact with the center disc 25 connected to one end of the secondary of transformer 18, and spring 30, projecting from and connected to plate 13, makes contact with flange 26 on tube 20 which in turn is connected to the other terminal of the secondary of transformer 18, thus completing the electric circuit for the operation of the neon lamp.

It should be noted that socket 15 is free to rotate about tube 3 and that in no matter what position it is rotated springs 29 and 30 always make contact with center plate 25 and flange 26, respectively. When turned to the proper position, the socket 15 is secured to tube 3 by tightening a set screw 33.

In the preferred form of my invention, the signal is energized independently of external power circuits by a battery contained within the column 3. With this arrangement, referring to Fig. 5, a tubular shell 19a is provided within the column 3, surrounding the tubular members 19 and 20, to which it is attached, and extending a substantial distance therebelow. The shell 19a is supported within the column 3 from the tubular member 20, which as previously described in connection with Fig. 3, is provided with an outwardly extending flange 21, which rests upon the upper edge of the column 3. The shell 19a has a portion, less than half, of its front wall cut away immediately below the member 19, as shown at 35 in Fig. 6, to permit access to the interrupter 17. The portion of the shell below the interrupter 17 holds a plurality of standard dry cells 34 mounted one above the other, the lowermost cell resting upon the bottom 19c of the shell 19a and the remaining cells being retained within the shell by clips 19b. Clips 19b are used because, as shown in Fig. 5, the body of the shell below interrupter 17 comprises only a semicyclindrical

80 wall, open at the front to permit removal and insertion of the batteries. Clips 19b are resilient and normally firmly grip the batteries, but may be spread apart when removing or inserting batteries. The batteries are connected together and to the interrupter 17 by wires extending vertically along the front surfaces of the batteries in the space between the batteries and the outer column 3, which space exists by virtue of the facts that the batteries are positioned concentrically within the column 3, and the front side of the shell 19a is open. Thus there is a space between the batteries and the column 3 equal at least to the thickness of the wall of shell 19a.

85 To change batteries, the entire assembly including tubular members 20 and 19, and shell 19a is lifted out of the column 3, the old batteries pulled out of the shell through the open side thereof, the clips 19b spreading to permit the removal, new batteries pushed into the shell past the resilient clips 19b, the batteries connected to each other and to the interrupter 17, and the assembly lowered into the column 3.

90 Of course, it is obvious that if desired the clips 19b may be dispensed with and each battery 34 100 permitted to rest upon the battery therebelow, the bottom battery being supported upon the bottom of the shell.

95 When using the dry batteries, as described, flasher switch 17 is preferably of a type in which the circuit from the battery through primary winding the transformer 18 is closed only momentarily, whereby each time the circuit is made and broken through the primary of the transformer, an impulse of current is generated in the secondary which momentarily energizes the neon lamp 4 and produces a flashing illumination through the stenciled openings in plate 1, outlining the word to be displayed. Flashing switches of the type utilized in this invention are 110 well known in the art, and do not form a part of this invention.

115 I claim:

120 A traffic signal comprising a tubular member open at the top, an inner member fitting within and supported from the top of said tubular column comprising an upper tubular member having an outwardly projecting flange at the top thereof, and an inwardly projecting flange at the bottom thereof, a lower tubular member having an inwardly extending flange at the top thereof, a disc of insulating material positioned horizontally within said tubular column between the lower flange on said upper inner member and the upper flange on said lower inner member, means for clamping said member between said flanges, a conductive terminal disc secured to the center of said insulating disc and spaced from the inner edges of said flanges clamping said insulating disc, a signal head comprising a sign, an electric lamp for illuminating said sign, a socket member secured to said signal head into which terminals of said lamp project, and brushes attached to said terminals adapted to engage the said conductive plate in said disc and the lower flange in said inner tubular member, respectively, and a source of electric energy mounted within said lower tubular member and connected to said conductor plate and said flanges on said inner tubular members respectively.
